UNITED STATES PATENT OFFICE

2,439,496

FLASHLIGHT

Daniel Szentay, Chicago, Ill.

Application February 18, 1946, Serial No. 648,510

5 Claims. (Cl. 240—10.68)

1

This invention relates to flashlights and more particularly to flashlights of the tubular type adapted to be held in and operated by one hand.

One of the objects of the invention is to provide a flashlight which is simple and inexpensive to construct and assemble and which comprises a minimum number of parts.

Another object is to provide a flashlight which is controlled by turning a cap on the main flashlight body.

Still another object is to provide a flashlight in which the switch mechanism is formed by a contact strip engageable with the battery and movable out of engagement therewith.

Still another object is to provide a flashlight in which the contact strip serves also to hold the cap assembly on the body.

The above and other objects and advantages of the invention will be more readily apparent from the following description, when read in connection with the accompanying drawing, in which—

Figure 1 is an axial section with parts in elevation of a flashlight embodying the invention;

Figure 2 is a view with the cap in section and the main body in elevation showing the flashlight in its "on" position;

Figure 3 is a view similar to Figure 2 showing the flashlight in its "off" position;

Figure 4 is a section on the line 4—4 of Figure 2;

Figure 5 is a section on the line 5—5 of Figure 3;

Figure 6 is a partial perspective view showing the interior of the body; and

Figure 7 is a perspective of the supporting member.

The flashlight, as shown, comprises a main body 10 of tubular form closed at one end and open at its opposite end. The body is preferably of non-conducting material, such as molded plastic and may be fluted or roughened throughout the major part of its length to improve its appearance and to facilitate holding it.

The open end of the body is closed by a cap 11, also preferably of molded plastic material in tubular form which fits rotatably over the open end of the body 10. The outer end of the cap is closed by a transparent cover 12 which may be cemented or otherwise permanently secured in place. The body is formed with an inwardly projecting shoulder 13 adjacent the cover 12 against which a bowl shaped reflector 14 is adapted to seat. The reflector 14 carries a lamp 15 having a base terminal 16 to engage the cen-

2

ter terminal 17 of a battery in the body. As shown, the lamp is threaded into the reflector although other holding means could be employed to hold the lamp in the reflector and to establish contact between the lamp base and the reflector.

The reflector is held in the cap by a supporting member 18 which is circular to fit slidably within the cap to be held therein by friction. The supporting member is prevented from rotation in the cap by providing it with a peripheral notch 19 to fit over a fin or rib 20 on the interior of the cap. With the reflector and supporting member in place, the supporting member will hold the reflector in the cap against the shoulder 13 and will be in conducting relationship with the base of the lamp 15.

To complete the circuit to the lamp, the reflector is formed with an axially extending contact strip 22 which projects into the body 10 and engages the side of the battery, as shown in Figure 1. The battery employed is uncovered adjacent its upper end so that when the contact strip engages its side, a circuit is completed from the outer terminal of the battery through the contact strip and lamp base to the base terminal 16 of the lamp and the center terminal 17 of the battery.

According to one feature of the invention, the contact strip serves the additional purpose of holding the cap assembled on the body. For this purpose, the body is formed with an internal peripheral groove 23 and the contact strip is bent outwardly, as shown at 24, to form a projection fitting into the groove. With the parts assembled, as shown, the projection 24 engages the groove 23 to prevent accidental removal of the cap from the body while permitting limited rotation of the cap on the body. To remove the cap from the body, it may be pulled axially to spring the projection inwardly so that the cap can be removed.

To disconnect the lamp from the battery, means are provided to move the contact strip away from the side of the battery. As shown, this means comprises an integral flap 25 extending inward from the body adjacent one end of the groove 23. When the cap is turned to the position shown in Figures 3 and 5, the flap 25 will engage the contact strip 22 and separate it from the side of the battery. To light the light, the cap need only be turned back to the position of Figures 1 and 4 in which the contact strip is out of register with the flap 25 and can spring into engagement with the side of the battery.

It will be seen that the present invention pro-

vides an extremely simple construction which can be manufactured inexpensively and which can easily be held in and controlled by one hand.

While one embodiment of the invention has been shown and described in detail, it is to be understood that this is illustrative only and is not to be taken as a definition of the scope of the invention, reference being had for this purpose to the appended claims.

What is claimed is:

1. A flashlight comprising a tubular body adapted to hold a battery, a cap fitting rotatably on the body, a lamp mounted in the cap in a position to engage the center terminal of a battery in the body, a resilient contact strip in the cap connected to the lamp and extending into the body and resiliently biased into engagement with the side of the battery, and an insulating flap extending inward from the side of the body to move the strip away from the battery when the cap is turned to one position.

2. A flashlight comprising a tubular body adapted to hold a battery, a cap fitting rotatably on the body, a lamp mounted in the cap in a position to engage the center terminal of a battery in the body, a contact strip in the cap connected to the lamp and extending into the body to engage the side of the battery, interengaging parts on the contact strip and the body to hold the cap against axial displacement on the body while permitting rotation thereof, and an insulating flap on the body extending inward from the side thereof to move the contact strip away from the battery when the cap is turned to one position.

3. A flashlight comprising a tubular body adapted to hold a battery, a cap fitting rotatably on the body, a lamp mounted in the cap in a position to engage the center terminal of a battery in the body, a contact strip in the cap connected to the lamp and extending into the body to engage the side of the battery, the body having a circumferentially extending groove on its interior, the strip having a projection thereon to fit into the groove to hold the cap against axial displacement on the body, and an insulating flap extending inward from the side of the body to move the strip away from the battery when the cap is turned to one position.

4. A flashlight comprising a tubular body adapted to hold a battery, a tubular cap fitting rotatably on the body, a transparent cover on the outer end of the cap, a reflector in the cap to carry a lamp in a position to engage the center terminal on a battery in the body, a supporting member fitting in the cap and engaging the reflector to hold it in the cap, an axially extending contact strip on the supporting member extending into the body to engage the side of the battery, and an insulating flap extending inward from the side of the body to move the strip away from the battery when the cap is turned to one position.

5. A flashlight comprising a tubular body adapted to hold a battery, a tubular cap fitting rotatably on the body, a transparent cover on the outer end of the cap, a reflector in the cap to carry a lamp in a position to engage the center terminal on a battery in the body, a supporting member fitting in the cap and engaging the reflector to hold it in the cap, an axially extending contact strip on the supporting member extending into the body to engage the side of the battery, the body having a circumferentially extending groove on its interior, the strip having a projection thereon to fit into the groove to hold the cap against axial displacement on the body, and an insulating flap extending inward from the side of the body to move the strip away from the battery when the cap is turned to one position.
